UNITED STATES PATENT OFFICE.

WALLACE D. KIMBALL, OF NEW YORK, N. Y., ASSIGNOR, BY MESNE ASSIGNMENTS, TO
NASHUA GUMMED & COATED PAPER COMPANY, OF NASHUA, NEW HAMPSHIRE.

METHOD OF MAKING STAY STRIPS FOR BOXES.

Application filed July 14, 1917, Serial No. 180,584. Renewed September 19, 1922. Serial No. 589,233.

To all whom it may concern:

Be it known that I, WALLACE D. KIMBALL, a citizen of the United States, and a resident of the city, county, and State of New York, 5 have invented new and useful Improvements in Methods of Making Stay Strips for Boxes, of which the following is a specification.

This invention relates to a method of making stay strips for boxes.

10 In the art of staying boxes, particularly hat boxes, where the stay strip connects the flat bottom of the box to the cylindrical wall, it has been the practice to cut the stay strip transversely of the web of the paper in order that the strip may be somewhat elastic 15 and thus allow the edge connected to the cylindrical portion of the box to stretch as it is applied to the box, so that the other edge will fold down flat against the bottom of the 20 box without wrinkling, as would necessarily occur with a stay strip incapable of stretching.

It is well known that paper is much more elastic across the web than in the direction 25 of the web, for the reason that the paper is drawn through the paper-making and calendering machine in the direction of the web and is stretched in the making in that direction, but not in the transverse direction. 30 It has therefore been necessary in the art of staying hat boxes and others in which the two edges of the stay strip are applied to surfaces of equal length, to cut the stay strips across the web and apply them singly 35 by hand. This method of procedure is much slower than when the stay strip is automatically fed and cut off the required length for application to the box by modern strip-serving machines such as generally employed in 40 the manufacture of boxes of a shape such that stay strips cut in the direction of the web may be used.

By the method of producing stay strips forming the subject-matter of my present invention, 45 I provide a stay strip in a continuous length for use in the strip-serving machines, but cut transversely of the web so as to have all the advantages of the separately cut stay strips heretofore used.

50 A further object of my invention is to provide a method of forming stay strips of this character which will be little, if any, more expensive than the production of ordinary stay strips running in the direction of the web.

In the accompanying drawings I have illustrated in Figs. 1, 2 and 3 the several steps in the method of making my improved stay strip, while in Figs. 4 and 5 I have shown in elevation and perspective, respectively, the 60 application of the stay strip to the box, and in Figure 6 I have shown a modified form of strip.

In manufacturing my improved stay strip I take a roll of paper of as great a width as 65 can conveniently be had in the desired quality, and gum one surface and reroll it in the manner usual in the manufacture of ordinary gummed tape. Instead, however, of slitting the roll into strips of the desired 70 width, I draw off from the roll 1 a length of the web as indicated at 2, and then cut from the end of the web by a transverse cut, a sheet 3 of a width as great as may be conveniently handled by the slitting machine. 75 This sheet 3 is then attached along one of its edges running parallel with the length of the web to the side edge of a similar sheet by means of a strip of tape 4 which is preferably of light stock, so as to add very little 80 to the thickness of the paper.

The connecting strip may be applied by moistening the strip on its ungummed side and applying it to the meeting edges of the sheets 3 on their gummed surfaces so that 85 the gummed surface of the strip will form with the gummed surfaces of the sheets a continuous gummed face on the web made up of the successively cut and attached sheets. The stay strip may, if desired, be 90 gummed on both faces to secure better adhesion to the meeting edges of the sheets, or the connecting strips may be applied to the ungummed face of the sheets as desired.

The web produced by thus cutting the 95 sheets from the web and attaching them with the grain of the original web, if it may be so termed, extending transversely of the made-up web, is wound into the roll and is then run through the slitting machine 100 which slits the web into individual strips as indicated at 5 in Fig. 3, each of which forms a separate roll 6 of gummed tape for use in the strip-serving machine.

In Figs. 4 and 5 I have shown the manner 105 of applying the strip to the box. Here the box body is shown at 7 and the bottom or end disk at 8. The strip-serving machine is adjusted to moisten and cut off a section 9 of the stay strip about equal to the circum- 110

ference of the box and without regard to the location of the connecting splices, so that one roll of tape may be used for any size box by merely adjusting the feed of the strip-serving machine.

The box-maker applies the moistened tape at the bottom edge of the box body, stretching the lower edge of the strip as he draws it around the circumference of the box body, thereby causing the unstretched and unattached upper edge of the strip to turn inwardly over the bottom of the box as shown in Fig. 4. After the edge of the stay strip is drawn around and attached to the box body, the other edge is pressed down against the box bottom, producing a smooth, un-wrinkled surface as indicated in Fig. 5.

If the small splicing piece is arranged as shown in Fig. 5 on the under side of the 20 tape, the spliced joint will not be noticeable in the finished box, the appearance of the joint being practically the same as that produced by the lapped ends of the stay strip.

25 A stay strip made according to my improved method has decided advantages in the box-making art. In the first place, a single roll of tape is adaptable for boxes of all diameters, whereas by the previous method, 30 the strips have to be cut from a web whose width is substantially equal to the diameter of the box, as otherwise there would be a considerable waste of paper. The chief advantage, however, is that with my improved stay strip, automatic moistening and cutting machines may be used by means of which the box-maker may produce an output in a given time greatly in excess of his previous production by the old method of moistening, 35 40 the previously cut strips. The saving in labor

bor more than offsets the additional cost of cutting and reassembling the sheets which make up the web.

Instead of connecting the separate sheets cut from the first web by means of spliced strips, as shown, the edges of the strips may be lapped one on the other, as indicated at 10 in Fig. 6, or any other approved method of connecting may be employed, if desired. 45

The term "grain" is used in the appended claim to mean the dimension of the paper parallel with the length of the web as originally produced, that is, with the same relation to the length as the grain of a piece of wood. 55

I claim: *(The following claims are directed to the invention in*

1. The method of making a strip which consists in cutting from the end of a web a series of sheets and reconnecting the sheets with the grain of the paper running at right angles to the direction of the grain in the original web, and thereafter slitting the made-up web into strips of the desired width. 60
  2. The method of making strips of gummed paper which consists in cutting from the end of a previously gummed web of paper having a longitudinal grain a series of sheets and reconnecting the sheets at their side edges to form a composite web having the grain extending transversely thereof and having a continuously gummed surface including the connected portions, and thereafter slitting said composite web into strips of the desired width. 65 70 75

Signed at New York city, in the county of New York and State of New York this 13th day of July, 1917.

WALLACE D. KIMBALL,
